(57) **CLAIM**

The ornamental design for a power station, as shown and described.

DESCRIPTION

FIG. 1 is a first front perspective view of a power station, showing our new design;
 FIG. 2 is a first rear perspective view thereof;
 FIG. 3 is a second front perspective view thereof;
 FIG. 4 is a second rear perspective view thereof;
 FIG. 5 is a front elevation view thereof;
 FIG. 6 is a rear elevation view thereof;
 FIG. 7 is a right side elevation view thereof;
 FIG. 8 is a left side elevation view thereof;
 FIG. 9 is a top plan view thereof;
 FIG. 10 is a bottom plan view thereof; and,
 FIG. 11 is a reference view thereof, showing the state in which the front cover is opened.
 The broken lines in the drawings illustrate portions of the power station that form no part of the claimed design.
